UNITED STATES PATENT OFFICE.

STEPHEN JARVIS ADAMS, OF PITTSBURG, PENNSYLVANIA.

SAND MOLD.

SPECIFICATION forming part of Letters Patent No. 521,449, dated June 19, 1894.

Application filed October 24, 1892. Serial No. 449,903. (No model.)

To all whom it may concern:

Be it known that I, STEPHEN JARVIS ADAMS, a resident of Pittsburg, in the county of Allegheny and State of Pennsylvania, have invented a new and useful Improvement in Sand Molds; and I do hereby declare the following to be a full, clear, and exact description thereof.

My invention relates to the pouring or casting of metal in sand molds, and to the construction of runners for feeding the metal to the pouring gates of these molds. In the formation of small sand molds, it has been practically universally the custom to form the sand molds independent of each other, the pouring gate or gates of each mold passing down from the top into the body of the mold, and to cast or pour the metal by means of hand ladles which are carried by the workmen from the cupola to the molds, each ladle containing sufficient metal to pour from one to four molds or more, according to the size of the molds, and it being necessary for the workmen not only to carry the metal to the molds, which was laborious and occupied considerable time on account of the distance from the cupola to the molds, but to support the ladle while he directed the stream therefrom into each pouring gate of the molds; this requiring skill and being practically the heaviest work in the formation of small hand molds. When it is appreciated that some molders can make between three and four hundred molds per day, and that it is necessary for them to carry the metal from the cupola or main ladle receiving the metal therefrom to these molds, and to make a sufficient number of trips to pour all the molds, it will be understood that this work occupies a large portion of the day, and is very wearing to the workmen, while at the same time it is practically impossible to feed the metal to the molds as rapidly as desired, and as the metal is exposed within the hand ladles it will chill more or less and the molds are not cast with the metal at as high a heat as necessary, thus causing a great deal of defective work.

The present invention consists, as generally stated, in combining with a series of sand molds a single trough extending over the same, said trough having openings therein and tubular leaders extending from the open-

ings of the trough to the pouring gates of the molds, said tubular leaders being rigid with the trough and detachable from the molds so that the trough with the tubular leaders can be transferred from one set of molds to another.

It also consists in the construction of such tubular leaders which form columns of metal above the bodies of the molds, and so act to insure a full supply of metal to the mold cavities and the formation of solid castings.

It also consists in the construction of a receiving basin for feeding the metal to such inclined trough.

It also consists in certain other improvements which will hereinafter be more fully set forth and claimed.

To enable others skilled in the art to make and use my invention, I will describe the same more fully, referring to the accompanying drawings, in which—

Figure 1 is a longitudinal section of the series of molds with a portable receiving basin showing my invention applied to the same. Figs. 2 and 3 are cross sections illustrating the form of tubular leader for conducting the metal to the pouring gate of the mold. Fig. 4 is a longitudinal section of a series of molds showing the basin formed as part of the runner. Fig. 5 is a cross-section of such a mold as shown in Fig. 4.

Like letters of reference indicate like parts in each of the views.

In practicing my invention, I prefer to employ the form in which the series of molds A are supported on a level bed or platform B, this bed or platform being either the foundry floor or a wooden or like platform on which the molds may rest, and in some cases the platform being movable, that is mounted on a car or truck, so that if desired the entire series of molds may be brought to the pouring ladle or to the cupola, and may be poured when close to the same and then be carried by the truck away from the same, so that another set of molds may be brought into the pouring position.

The inclined trough C is preferably formed of metal and lined with fire clay, asbestos, or some similar heat protecting material, and is preferably arranged at such an incline that the metal will flow down the same from the

pouring basin D arranged at the upper end thereof. The trough C has the pouring openings c formed therein above the pouring gates of the molds and extending from such pouring openings to the pouring gates are the tubular leaders e, these leaders being preferably formed with the trough, so that they may be placed upon and lifted from the set of molds with the trough, and being of different lengths corresponding to the distances between the pouring openings and the pouring gates of the respective molds where the trough is inclined. The particular form of leaders preferred is illustrated in Figs. 2 and 15 3, and in Fig. 3 the leader is illustrated as separate from the trough, in which position it may be in some cases employed even in pouring single molds, so that the advantages of insuring a sufficient body of metal to fill 20 the molds and a weight of molten metal to compact the castings formed in the mold may be utilized either in the single molds, or in pouring the series of molds as shown in Fig. 1. The tubular leaders e have formed at the 25 bases thereof annular lips e' which are adapted to press into the sand of the molds and form a tight joint between the annular leaders or mold coverings and the sand of the molds, so as to prevent leakage from the leaders over the tops of the sand molds.

In Fig. 2 I have illustrated the tubular leader with a flat block therewith and extending out over the surface of the sand mold, such flat blocks e² forming mold weights to 35 confine the sand of the molds during the casting operation, and to hold any cores within the mold cavities where such cores enter through the tops of the molds. The tubular leaders are preferably formed of metal, and 40 have linings of fire brick or like refractory material, as at f. These refractory linings are inserted either through the base of the leaders, as shown in Fig. 2, or through the top of the same, as shown in Fig. 3. In the 45 former case, the inner walls of the tubular leaders are tapering toward the top, and the refractory linings, if brought to shape before being inserted, are correspondingly tapered so as to fit therein; and a tight joint between 50 the upper ends of the tubular linings and the leaders may be formed by the use of fire clay. The linings may, of course, be molded within the tubular leaders.

In Fig. 3 the mold weights are formed separate from the tubular leaders, fitting around the same and resting on the sand molds.

As the metal flows down the inclined pouring trough or runner, its flow may be checked in any suitable way by means of a dam which 55 will direct the same into the tubular leader until the particular mold with which it communicates is filled, and such dam may be formed by means of a groove or seat h formed in the trough into which any suitably shaped 60 block or dam h' may be placed as the metal flows down the trough. I may also employ the dams formed in the body of the trough,

as shown at i, such dams being formed at the back of each opening communicating with the tubular leader so that the metal will strike 70 against the same, and cannot pass over it until it fills that mold, after which it will flow over such dam to the next opening, the molds being thus successively filled as the metal passes down through the trough. In the latter case the metal will fill the pockets formed by such dams, but a slight blow or movement before the metal is set (while it is brittle and weak) will break it from the metal in the leader so that the trough can be easily removed from the series of molds.

For the feeding of the metal to the trough, I may employ either a basin formed with the trough, or, as preferred by me, a removable basin communicating with the trough, such 85 removable basin being placed at the pouring end of the series of molds, and resting on the foundry floor or platform, this being illustrated in Fig. 1. By the employment of the basin feeding the trough, the metal 90 is properly directed into the same and the necessity of such careful pouring from the large ladle is overcome. In the preferred construction of basin, the basin k is supported on a frame k' and is hinged or pivoted at 95 the end nearest the trough, as at k², so that the basin may be raised by the operator to feed all the metal therefrom into the trough, or to regulate the feeding of the metal during the pouring operation. For this purpose any 100 suitable mechanism for raising the rear end of the basin may be employed, that shown being the segmental geared arm l extending down from the basin with which a pinion k³ mounted on the frame k' engages, said pinion being turned by a suitable handle, and so providing for the raising of the rear end of the basin to feed the metal therefrom into the trough. Preferably at the forward end or mouth k⁴ of the basin is hinged a spout m 105 which extends down to and rests within the trough so forming a continuous course from the basin into the trough, as the mouth of such movable spout can rest in the pouring trough and when the basin is raised or lowered the spout will simply swing on its pivot m' and so form a continuous course for the metal from the basin to the trough, no matter in what position the basin is supported. Such construction provides for the proper connection of the basin with the pouring trough, 110 no matter what the relative position of the trough and the basin may be. Such pivoted spout may also be used directly with the ladle, and in such case the basin will not be required. At the end of the continuous runner is the receiving basin t into which any 115 surplus metal after the filling of the molds can flow, so preventing the spilling of the metal upon the floor. This basin may be of any suitable construction. As the metal is passing along the inclined trough to the several pouring gates, there is a liability of its 120 becoming chilled by contact with the air and 125 130

so not flowing as freely as desired to the different molds, especially at the lower end of the trough; and to prevent this chilling of the metal I prefer to employ a removable runner cover *p* which rests upon the runner and so prevents the contact of the air with the molten metal and maintains the heat of the metal as it flows through the runner. This runner cover is preferably raised in the center as shown by *p'*, that is, having the central longitudinal raised portion *p'* and the lips or ribs *p*² extending out at each side to support the cover upon the runner, such raised portion preventing the direct contact of the metal with the cover, and also permitting the free escape of the gases as the metal flows through the runner. Such cover can, of course, be employed with any form of continuous runner where the metal is fed at one end thereof, and flows thence to the several pouring gates of the molds.

The manner in which the inclined trough is employed, will, of course, be easily understood the metal being carried to the same in any suitable ladle which can be supported on any over-head or ground track, and being poured into the basin *k*, from which it flows directly into the upper end of the trough, flowing down the same until it reaches the first opening therein, and the metal being checked in its course either by the hand stopper or dam *h'* preferably fitting in the groove *h*, or by the dam *i* formed in the body of the trough and the metal then flowing down the tubular leader *e* into the pouring gate *a* and thence to the mold cavities, and as the tubular leader is filled, the body of molten metal therein acting as a sinker head or feeder to the mold so that it will insure the formation of solid castings, the metal thus passing down through the trough from mold to mold, filling each mold successively in its course. The feeding of the metal may be regulated by the operator by raising or lowering the feeding basin, and as the stream of metal approaches the last mold in the series, the basin may be raised so that when said mold has been filled all the metal has been emptied from the basin. On account of the lips *e'* at the lower ends of the tubular leaders which press into the sand and form close joints therewith, all liability of the metal escaping at the tubular leaders is overcome. At the same time the cover *p* if employed will protect the molten metal from contact with the air, maintaining it at a high heat until it reaches the lower end of the runner. As soon as the metal is set, the trough or troughs may be lifted from the series of molds and placed upon another series of the same, the cores or sinker heads formed in the tubular leaders passing out of the same when the trough is lifted off, or being easily driven from the same in their weak unsettled state if they stick therein. The refractory linings can be easily replaced in the tubular leaders in case they break or wear out.

As before stated, the tubular leaders may be employed with separate molds, and in that case act as sinker heads therefor. This feature is of special importance, as it enables me to reduce the thickness of the body of the mold, only sufficient sand to hold the metal in forming the casting being used, and the metal in the leader feeding to the mold cavity the metal necessary to form a solid casting.

What I claim as my invention, and desire to secure by Letters Patent, is—

1. In combination with a series of sand molds set upon a level floor or platform, a trough extending over the same and having openings therein, and tubular leaders extending from such openings to the pouring gates of the several molds, said leaders being rigid with the trough and detachable from the molds, and the passages in the leaders being tapering toward the upper end, substantially as and for the purposes set forth.

2. In combination with a sand mold, a removable tubular leader extending up from the pouring gate of the mold, and having a block at the base thereof resting on and forming a mold weight for the mold, substantially as and for the purposes set forth.

3. In combination with a sand mold, a runner resting on and extending up from the pouring gate of the mold, and having an annular lip at the base thereof to press into the sand of the mold and form a close joint therewith, substantially as and for the purposes set forth.

4. In combination with a sand mold, a removable tubular leader extending up from the pouring gate of the mold, and having a refractory lining the inner walls whereof are tapering toward the top, substantially as and for the purposes set forth.

5. The combination with a series of sand molds, of a continuous runner extending over the same and communicating with the pouring gates of the several molds, and a feeding basin adapted to receive the metal from the ladle and feed it to the runner, said basin being mounted at its forward end so as to be raised to feed the metal to the runner, substantially as and for the purposes set forth.

6. The combination with a runner for feeding metal to sand molds, of the frame *k'*, the feeding basin *k* mounted on said frame, and having the geared segmental arm and the pinion *k*³ engaging therewith, substantially as and for the purposes set forth.

7. The combination with a runner for feeding metal to sand molds, of a feeding basin mounted so as to be raised to feed the metal to the runner, and a feeding spout hinged to the mouth of said basin and adapted to feed the metal into said runner, substantially as and for the purposes set forth.

8. The combination with a series of sand molds of a runner extending along the same and adapted to feed the metal to the pouring gates of the several molds, and a runner-cover adapted to fit over said runner and re-

movable therefrom, substantially as and for the purposes set forth.

9. The combination with a series of sand molds, of a runner extending along the same and adapted to feed the metal to the pouring gates of the several molds, and a removable runner cover adapted to fit over said runner said cover having a raised central portion p' , substantially as and for the purposes set forth.

10. In combination with a series of sand molds, a trough extending over the same and having openings therein, and tubular leaders extending from said openings to the pour-

ing gates of the several molds, said leaders being rigid with the trough and detachable from the molds, and said leaders having annular lips at the base thereof to press into the sand of the mold and form close joints therewith, substantially as and for the purposes set forth.

In testimony whereof I, the said STEPHEN JARVIS ADAMS, have hereunto set my hand.

STEPHEN JARVIS ADAMS.
